UNITED STATES PATENT OFFICE.

DOLPHUS S. ADAMS, OF BISHOP, GEORGIA.

LOCK DEVICE.

1,284,029.

Specification of Letters Patent.

Patented Nov. 5, 1918.

Application filed January 10, 1918. Serial No. 211,220.

To all whom it may concern:

Be it known that I, DOLPHUS S. ADAMS, a citizen of the United States, residing at Bishop, in the county of Oconee, State of Georgia, have invented certain new and useful Improvements in Lock Devices; and I do hereby declare the following to be a full, clear, and exact description of the invention, such as will enable others skilled in the art 10 to which it appertains to make and use the same.

This invention is an improvement in lock devices and has particular reference to a lock for application to the exhaust pipe of 15 an automobile.

An object of the invention is to provide a lock device to be applied to the connection between the exhaust manifold and pipes of an automobile whereby said connection will 20 be prevented from becoming loose with a consequent danger of the gases from the pipe escaping and causing fire or other damage to the machine.

Another object is to provide a lock device 25 of this character which is simple in construction, easy to manufacture and effective in carrying out the purpose for which it is designed.

The inventive idea involved is capable of 30 receiving a variety of mechanical expressions one of which, for the purpose of illustrating the invention, is shown in the accompanying drawing, wherein:—

Figure 1 is a fragmentary side elevation 35 of an exhaust pipe and manifold showing the invention applied thereto.

Fig. 2 is a longitudinal section thereto.

Fig. 3 is a perspective view of the lock device in opened position.

40 In the drawing, the numeral 5 indicates an exhaust manifold pipe to which is connected, in the usual manner by a nut 6, the exhaust pipe 7.

The lock device which comprises the essential feature of this invention is adapted 45 to be applied to the exhaust pipe so as to engage the nut 6 and lock the same against turning so that the connection between the manifold and pipe will be securely maintained and said device preferably comprises a pair of complemental sections 8 hinged together at 9 along adjacent longitudinal edges. When the sections are in closed or operative position the same are preferably

of hexagonal formation so that adjacent 55 ends of the section will engage the sides of the similarly shaped nut 6. It is to be understood, of course, that the sections 8 may be of square or other formation depending upon the number of sides with which the 60 nut is provided. The longitudinal edges of the sections 8 opposite the hinge 9 are provided with lugs 10 having openings 11 therein adapted to register, when the sections are closed, for receiving a locking bolt 12 which 65 extends through said openings and which is secured in position by a nut 13.

Each section 8 is further provided, upon the end thereof opposite the one which engages the nut 6, with an inwardly directed 70 substantially semicircular flange 14 the inner curved edges of which are provided with the teeth or serrations 15 which combine with the teeth of the opposite flange to tightly grip the pipe 7 and prevent longitudinal and 75 rotary movement of the lock device relative thereto after the bolt 12 has been tightened.

In practice, the device is applied so that the ends of sections 8 opposite the flanges 14 will be engaged with the sides of the nut so 80 that the same will be recessed within said ends and when the sections are brought to closing position the teeth 14 will engage the pipe 7 after which the bolt 12 may be secured to the lugs 10 and by tightening said 85 bolt it will be apparent that the teeth 15 will be caused to bite into the pipe thus preventing any movement of the device relative thereto. In this manner, any turning movement of the nut 6 and consequent 90 loosening of the connection between the pipe and manifold due to vibrations of the engine will be prevented.

What is claimed is:—

1. A lock device of the character described, comprising complemental sections pivoted together and adapted to embrace the exhaust pipe of an engine and the connection therebetween and the manifold, adjacent ends of said sections having inwardly 95 directed and coacting flanges provided upon their inner edges with serrations adapted to grip said pipe, and means connecting the sections for clamping the same to said pipe and connection. 100

2. A lock device of the character described, comprising complemental sections of transverse angular formation pivoted to- 105

gether and adapted to embrace the exhaust pipe of an engine in spaced relation and also engage the connection between said pipe and the manifold, flanges disposed at the ends of 5 the sections opposite those engaging said connection and provided with serrations engaging the exhaust pipe to prevent relative movement of the device with respect thereto,

and means connecting the sections for clamping the same to said pipe and connection. 10

In testimony whereof, I affix my signature, in the presence of a witness.

DOLPHUS S. ADAMS.

Witness:

C. E. JONES.
